Gifford & Bull.

ATTORNEY

UNITED STATES PATENT OFFICE.

ELTON L. TOWLE, OF PATERSON, NEW JERSEY, ASSIGNOR OF ONE-HALF TO GEORGE DE LAVAL, OF ORANGE, NEW JERSEY.

VALVE.

1,355,367.

Specification of Letters Patent. Patented Oct. 12, 1920.

Application filed March 5, 1919. Serial No. 280,841.

To all whom it may concern:

Be it known that I, ELTON L. TOWLE, a citizen of the United States, residing at Paterson, in the county of Passaic and State 5 of New Jersey, have invented certain new and useful Improvements in Valves, of which the following is a specification.

This invention relates to valves of the type employing a thin flexible valve member and especially adapted for use in pumps 10 for air or other gases.

One of the objects of the invention is to provide such a valve which is inexpensive to manufacture and maintain and which is 15 positive in its action.

With these and other objects in view my invention consists of certain novel features of construction, combination and arrangement of parts as will be more fully described 20 and pointed out in the appended claims.

In the drawings Figure 1 is a plan, with some of the parts partially broken away, of a square plate valve of a form which I have adopted for purposes of illustration, showing one arrangement of my novel valve; Fig. 2 is a vertical section on line 2—2 of Fig. 1; Fig. 3 is a section on the line 3—3 of Fig. 2; Fig. 4 is a section on line 4—4 of Fig. 1; Fig. 5 is a bottom view of the valve 30 cap looking in the direction of the arrow 5 in Fig. 2; Fig. 6 is a cross section of a modification of the form of valve illustrated in Figs. 1 and 2.

The corresponding parts are referred to 35 both in the drawings and in the specification by similar reference characters.

In the illustrative form of valve, 10 is a valve seat member, the upper surface of which preferably is ground flat and true. 40 A series of ports 11 are provided on either side of the center line of the valve seat so that there is a solid central portion 12. If desired, the ports 11 may extend entirely across the valve seat.

45 Superimposed on the valve seat 10 is a valve cap 13 comprising, in the illustrative form, a rectangular plate with members 15 attached by suitable fastenings 19 to the cap 13. The cap 13 is provided with a series 50 of openings 18 which are located in staggered relation with the ports 11 in the valve seat.

55 In the form illustrated, the valve is a thin elastic strip 17 of steel or the like, which normally contacts with the flat face of the

valve seat 10 and extends across a pair of ports 11, there being as many of the strips 17 as there are pairs of ports 11.

In order to locate the valve 17 and to retain it in operative position in connection 60 with the valve seat 10, I provide a suitable recess 14 in the cap 13, which recess in the illustrative form is only slightly wider than the valve 17 and slightly longer than the valve, the ends of the recess being limited 65 by the members 15. These clearances permit the valve to have an entirely free motion in the recess.

Preferably I make the recess 14 angular to the face of the cap 13 with the shallowest 70 portion of the recess opposite the solid portion 12 of the valve seat 10, the recess at the point 16 being deep enough, however, not to subject the valve to any pressure. From the central portion 16 the recess increases 75 in depth, as shown best in Fig. 2, this depth being arranged so as to limit the amount of opening of the valve 17 without restricting its bending around the portion 16 in any manner.

When the valve is in use as, for instance, in an air pump, the pressure through the ports 11, will lift the valve 17 and bend it around its central portion and the central portion 16 of the valve cap 13. The fluid 85 passing through the ports 11 moves through the recess 14 and into the openings 18. As soon as the pressure is reversed the valve is drawn down to its normal position in contact with the valve seat.

It will be seen that I have provided a valve which is substantially unrestrained in its movement, while at the same time it is sufficiently confined so that it will never be displaced from its operative position. 95 Moreover, it will be seen that the valve is permitted to bend in the most natural way so that it can assume the curve which would be assumed by a uniformly loaded beam. Consequently, there are no undue strains on any portion of the valve whereby constant repetition of the bending will tend to break it.

While I prefer the arrangement illustrated, it will be obvious that my novel device may be varied within wide limits. For instance, instead of having a spring with both ends bending, it will be possible to employ one-half of the valve arrangement which I have illustrated, in which case the 100 105 110

valve seat would extend only slightly to one side of its center line in Fig. 2. In such case, the valve would bend around a substantially fixed end as the other end moved toward and away from the valve seat. Such an arrangement is illustrated in Fig. 6.

What I claim and desire to secure by Letters Patent of the United States is:—

1. A valve seat, a thin, elastic imperforate strip forming a valve, and a cap to maintain the valve in operative relation to the valve seat without pressure on any part of the valve, the cap being constructed and arranged to permit the valve to bend freely around its center portion to permit the ends of the valve to move toward and away from the valve seat while maintaining the center portion relatively stationary.
2. A valve seat, a thin, elastic imperforate strip forming a valve, and a cap to maintain the valve in operative relation to the valve seat without pressure on any part of the valve, the cap being constructed and arranged to permit the valve to bend freely around its center portion to permit the ends of the valve to move toward and away from the valve seat while maintaining the center portion relatively stationary, the cap being also arranged to limit the motion of the ends of the valve away from the valve seat.
3. A valve seat, a thin, elastic strip forming a valve, and a cap extending over the valve seat and provided with a recess for the valve, the recess being adapted to permit the valve to move bodily and to bend freely around its center portion to permit the ends of the valve to move toward and away from the valve seat while maintaining the center portion relatively stationary.
4. A valve seat, a thin, elastic strip forming a valve, and a cap extending over the valve seat and provided with a recess for the

valve, the recess being adapted to permit the valve to move bodily and to bend freely around its center portion to permit the ends 45 of the valve to move toward and away from the valve seat while maintaining the center portion relatively stationary, said recess being also adapted to prevent lateral and longitudinal displacement of the valve relatively to the valve seat.

5. A valve seat, a thin, elastic strip forming a valve, and a cap extending over the valve seat and provided with a valve recess slightly wider and longer than the valve and 55 with its bottom extending at an angle to the valve seat, the recess at one part being only slightly deeper than the thickness of the valve and at another part, opposite the end of the valve, considerably deeper than the 60 thickness of the valve.

6. A valve seat, a thin, elastic strip forming a valve, and a cap extending over the valve seat and provided with a valve recess slightly wider and longer than the valve and 65 slightly deeper at its center portion than the thickness of the valve and increasing in depth from its center portion to its ends.

7. A flat valve seat having a pair of elongated ports on either side of the center of the 70 valve seat, a thin, elastic imperforate strip forming a valve to cover the ports in the valve seat, and a cap extending over the valve seat and provided with openings out of alinement with the ports, the cap being provided with a valve recess slightly wider and 75 longer than the valve and slightly deeper at its center portion than the thickness of the valve and increasing in depth from its center portion to its ends, every part of said valve 80 being free to move within the limits of said recess.

ELTON L. TOWLE.
